WINE BOTTLE RACK

David M. Stravitz, 205 3rd Ave.,
New York, N.Y. 10003

Filed Dec. 28, 1970, Ser. No. 26,646

Term of patent 3½ years

Int. Cl. D6—99

U.S. Cl. D44—29

FIG. 1

FIG. 2

FIG. 3

FIG. 4

FIG. 1 is a front elevational view of a wine bottle rack showing my new design;

FIG. 2 is a rear elevational view thereof;

FIG. 3 is a side elevational view thereof, looking at FIG. 1 from the right side thereof; and

FIG. 4 is a top plan view thereof.

I claim:

The ornamental design for a wine bottle rack, substantially as shown.
